UNITED STATES PATENT OFFICE.

GEORGE H. CROFUT, OF DANBURY, CONNECTICUT, ASSIGNOR TO MALLORY HAT COMPANY, OF DANBURY, CONNECTICUT, A CORPORATION OF CONNECTICUT.

HAT AND ART OF MAKING THE SAME.

Application filed September 13, 1924. Serial No. 737,458.

To all whom it may concern:

Be it known that I, GEORGE H. CROFUT, a citizen of the United States, and a resident of Danbury, in the county of Fairfield and 5 State of Connecticut, have invented an Improvement in Hats and Art of Making the Same, of which the following is a specification.

This invention relates to hats and more 10 particularly to straw hats.

One of the objects of the invention is to provide a straw hat of practical construction capable of meeting the requirements of use in a highly satisfactory manner. Another 15 object is to provide such a hat adapted to fit comfortably upon the head of the wearer and hold its shape. Another object is to provide a hat of the above nature which is strongly constructed and durable. Another 20 object is to provide such a hat having an attractive appearance and capable of retaining such appearance in use. Another object is to provide a practical and efficient art of making such straw hats which may conveniently be carried on. Other objects will 25 be in part obvious or in part pointed out hereinafter.

The invention accordingly consists in the features of construction, combinations of 30 elements, arrangements of parts and in the several steps and relation and order of each of the same to one or more of the others, all as will be illustratively described herein, and the scope of the application of which will be 35 indicated in the following claims.

In the accompanying drawing, in which is shown one of the various possible embodiments of this invention,

Figure 1 is a perspective of a straw hat 40 body;

Figure 2 shows a short length of straw braid;

Figure 3 is a perspective of the under brim of the hat showing the bottom surface 45 thereof;

Figure 4 is a vertical section showing the under brim apart from the upper portion of the hat;

Figure 5 is a perspective showing a portion 50 of the hat while in the process of making, and

Figure 6 is a view of a fragment of the hat body.

Similar reference characters refer to similar parts throughout the several views of the 55 drawing.

Referring now to the drawing in detail, there is shown in Figure 1 a perspective of a straw hat body showing the crown 10 and the upper surface of the brim 11. This hat 60 is made of straw braid which is coiled in a spiral with its edges overlapping, the contiguous rows of the straw braid being secured together, as by stitching, to form the hat body, as will be described in detail. In 65 Figure 2 there is shown a short length of the straw braid of which the hat shown in the drawing is made. This straw braid, as will be seen, is woven so as to present a substantially smooth or regular edge 12 and an irregular edge 13, the latter being shown herein as a serrated or saw-toothed edge. It is to be understood that the straw braid may be of various patterns and of various forms of weaving, the irregular edge 13 thereof as 70 suming various forms and shapes, and that the term irregular edge as employed herein is to be interpreted throughout in a broad sense to comprehend these various shapes and forms. Moreover, the term smooth 75 edge is employed broadly to denote the edge of the straw braid other than the irregular edge.

The straw hat shown in the drawing is preferably made with a double brim, but it 80 is to be understood that the features of this invention may be embodied in a single brim hat. As is best shown in Figure 4, the crown 10 and the upper brim 11 are made in one piece and the lower or under brim 14 85 is separately made and subsequently secured thereto. The under brim is made preferably with an upwardly projecting rim 14^a which fits within the lower portion of the crown 10, and the outer edge of the under 90 brim mates with the outer edge of the upper brim 11.

This straw hat is of the stiffened type, the crown and brim thereof being adapted to be 100 stiffened by suitable means so as to be relatively hard and inflexible. This stiffening is preferably brought about by the application of a gelatinous stiffening material which is applied to the sewed hat. A hat which is thus rigidly stiffened throughout is 105 objectionable in that it does not fit com-

fortably upon the head and will not conform readily to the shape of the head of the wearer. In order to overcome this objection the band portion of the hat is stiffened to a lesser extent than the remaining portions of the hat by employing thereat a weaker or different stiffening, or in some instances by altogether omitting the stiffening at the band portion of the hat.

By 5 the band portion, it will be understood, is meant the region of the hat substantially at the intersection of the crown and brim. By leaving this portion of the hat yielding and flexible, the band easily assumes the shape 10 of the wearer's head giving an even pressure against the head at all points and providing a comfortable fit.

A hat of this type, however, having a stiff crown and brim and a soft yielding band 20 portion when made in the usual manner is open to the objection that it does not hold its shape. The soft band permits the brim to warp and twist out of position, thus detracting greatly from the appearance and 25 wearing qualities of the hat. Moreover, difficulty is encountered in that the sewed rows of braid at the soft band portion separate and open up as this portion of the hat is repeatedly flexed, giving a very unsightly 30 appearance to the hat. To provide a straw hat with a soft yielding band which overcomes such difficulties as these in an effective manner is one of the dominant aims of this invention.

35 Referring now again to Figure 4, the straw braid comprising the crown 10 and upper brim 11 is seen to be lapped in the same direction throughout, the exposed edge being directed outwardly from the tip 15 of the hat. The braid of the under brim 14 is also lapped in the same direction throughout with the exposed edge directed outwardly toward the edge of the brim. As is seen in Figure 1, throughout the major portion 40 of the crown 10 and of the brim 11, the irregular edge of the braid is directed away from the tip 15 and overlaps the smooth edge. At the lower portion of the crown and the inner side of the brim, however, or at the band portion of the hat, the 45 smooth edge of the braid is directed away from the tip and overlaps the irregular edge. Also, as shown in Figure 3, at the outer and major portion of the under brim 14, the 50 irregular edge is directed outwardly and overlaps the smooth edge while at the inner portion thereof the smooth edge is directed outwardly and overlaps the irregular edge. Thus, at the band portion of the hat, the 55 portion which is stiffened to a lesser degree than the remainder of the hat to provide a comfortable fit, the straw braid is turned edge for edge so that the smooth edge overlaps and is exposed instead of the irregular 60 edge, but the direction of the overlap is the

same throughout. Also the kind of braid used is preferably the same throughout the hat. Furthermore, it will be noted from a consideration of Figure 2 that, irrespective of whether the smooth edge 12 or the irregular edge 13 is exposed, the conformation of the braid at both the edges 12 and 13 lends to the hat a continuity of ornamental appearance throughout.

In making the hat, the braid is sewed starting from the button or tip 15. The end portion of the strip of braid is first tightly coiled and sewed to form the button or tip 15, and thereupon the braid is sewed in a machine in overlapping spiral fashion working outwardly from the tip. As the spiral is formed by thus sewing together the adjacent rows of braid the resulting structure is shaped to substantially the contour of the crown of the hat forming the top surface of the crown and the side walls 10. At the start the irregular edge 13 of the braid is directed outwardly from the tip 15 and overlaps the smooth edge, this being continued to a point 16, for example, adjacent the band. Thereupon the strip is cut off, preferably diagonally as indicated, and reversed edge for edge, the sewing being from this point done with the smooth edge 12 directed away from the tip and overlapping the irregular edge 13. The sewing is continued in this fashion to a point 17, for example, on the brim. At this point the braid is again cut and again reversed edge for edge, the brim being completed with the 100 irregular edge of the braid directed outwardly and overlapping the smooth edge.

The under brim 14 is sewed starting from the inner end 18, as shown in Figure 3, with the smooth edge directed outwardly and 105 overlapping the irregular edge. This is carried on to a point 19, for example, where the braid is cut, reversed edge for edge and sewed therefrom with the irregular edge directed outwardly and overlapping the 110 smooth edge.

In sewing the crown 10 from the tip 15 to the point 16, a concealed chain stitch is employed, as is indicated at 20 in Figure 6. This concealed stitch is the type of stitch 115 generally employed in sewing straw braid hats, and is of advantage in that it shows little or not at all on the surface of the hat, as is brought out in Figure 6. This stitch, however, is weak in that it loops through such a small portion of the straw and is not strong enough to hold the slightly stiffened and flexible band portion of the hat with sufficient firmness to give it permanence of shape. From the point 16, therefore, the 120 braid is sewed with a type of stitch which is stronger and more firm than the concealed stitch. The stitch preferably employed at this portion of the hat is shown at 21 in Figure 6, and is preferably what is known 130

as a through and through chain stitch. This stronger stitching is employed in sewing the band portion of the hat, and is preferably continued to the point 17, whereupon 5 the stitch is again changed to the concealed stitch which is carried to the edge of the brim.

Thus, the relatively stiff and unyielding portions of the hat are sewed with the concealed stitch, whereas the relatively soft and yielding band portion of the hat is sewed with a stronger and firmer stitch and thereby reenforced. This reenforcement while not detracting from the softness and flexibility of the band to provide a comfortable fit, imparts such strength to the band portion that the finished hat will permanently retain its shape. This through and through chain stitch is of such nature that the rows 10 of braid at the band portion are held in such manner as to be able to slide upon each other, thereby contributing to the flexibility of the band of the hat, but the brim is not permitted to bend and warp out of shape.

25 In the hat constructed as above described, at the flexible portion of the brim near the band the smooth edge of the braid is the overlapping or exposed edge. As the hat is flexed at this portion in being handled, 30 therefore, the irregular edge of the braid being underneath, the points thereof do not become bent up on the upper brim nor down on the under brim so as to project and detract from the smooth finished appearance 35 of the hat. The smooth edge 12 which is exposed at this portion, moreover, is firmly held in place by the stitching 21.

From the above, it will be seen that there is herein provided a straw hat which attains 40 many advantages of greatest practical importance. A stiffened straw hat is provided which will afford a comfortable fit upon the head of the wearer and which at the same time will permanently retain its original 45 shape and appearance.

As many possible embodiments may be made of the mechanical features of the above invention and as the art herein described might be varied in various parts all 50 without departing from the scope of the invention, it is to be understood that all matter herein set forth or shown in the accompanying drawings is to be interpreted as illustrative and not in a limiting sense.

55 I claim as my invention:

1. In straw hat construction, a straw hat comprising rows of straw braid secured together and stiffened, the band portion being stiffened to a lesser degree than the 60 remaining portion of the hat and the braids of said band portion being secured together more firmly than the braids of the remaining portion of the hat.

2. In straw hat construction, a stiffened 65 straw hat having a band portion which is

yielding relative to the remaining portions of the hat, said hat comprising rows of straw braid sewed together, said yielding band portion being sewed with a stitch different from and more firm than that with 70 which the remainder of the hat is sewed and being thereby reenforced.

3. In straw hat construction, a stiffened straw hat having a band portion which is soft relative to the remainder of the hat, 75 said hat comprising rows of straw braid sewed together, the major portion thereof being sewed with a concealed stitch and said relatively soft band portion being sewed with a through and through stitch 80 for reenforcement.

4. In straw hat construction, a straw hat comprising overlapping rows of the same straw braid throughout, sewed together and stiffened, the band portion thereof being 85 stiffened to a lesser degree than the remaining portions of the hat and being yielding relative to the remaining portion of the hat, said band portion being sewed with a stitch different from and more firm than 90 that with which the remainder of the hat is sewed and being thereby reenforced.

5. In straw hat construction, a straw hat comprising overlapping rows of straw braid which has an irregular edge and a smooth 95 edge, said rows of braid being sewed together and stiffened, and said rows of braid overlapping so as to expose the irregular edge of the braid throughout the hat excepting for a portion adjacent the intersection of the crown and the brim of the hat, at which portion the said braid is reversed edge for edge so as to expose the smooth edge of the braid, said portion being stiffened to a lesser degree than the remainder of the hat and being sewed with 100 a stitch different from and more firm than that with which the remainder of the hat is sewed.

6. In straw hat construction, a straw hat 110 comprising overlapping rows of the same straw braid throughout, sewed together and stiffened, the band portion thereof being stiffened to a lesser degree than the remaining portions of the hat, said band portion being sewed with a through and through stitch and the remaining portion of the hat being sewed with a concealed stitch.

7. In straw hat construction, a straw hat comprising overlapping rows of the same 120 straw braid throughout, sewed together, the major portion of the crown and brim being relatively stiff and inflexible and sewed with a concealed stitch, and the band portion being relatively soft and yielding and 125 sewed with a stitch different from and more firm than said concealed stitch.

8. In straw hat construction, a hat comprising overlapping rows of straw braid having an irregular edge and a smooth edge, 130

- 5 said rows of braid overlapping so as to expose the irregular edge of the braid throughout the hat excepting for a portion thereof adjacent the intersection of the crown and the brim of the hat, at which portion the said braid is reversed edge for edge and the rows thereof being overlapped so as to expose the smooth edge of the braid.

10 9. In straw hat construction, a straw hat comprising overlapping rows of straw braid which has an irregular edge and a smooth edge, secured together and stiffened, said rows of braid overlapping so as to expose the irregular edge of the braid throughout the hat excepting for a portion thereof adjacent the intersection of the crown and the brim, said portion being stiffened to a lesser degree than the remainder of the hat and having the said braid reversed edge for edge so as to expose the smooth edge of the braid at said portion and the braid at said portion being secured together more firmly than the braid of the remainder of the hat.

15 10. In straw hat construction, a hat comprising overlapping rows of straw braid having an irregular edge and a smooth edge, the major portion of the crown and brim being relatively stiff and inflexible and the band portion being relatively soft and flexible, said rows of straw braid overlapping throughout the major portion of the crown and brim so as to expose the irregular edge of the braid and being reversed edge for edge at said relatively soft band portion so as to expose the smooth edge.

20 11. In straw hat construction, a hat comprising overlapping rows of straw braid having an irregular edge and a smooth edge, the upper portion of the crown and the outer portion of the brim being relatively stiff and inflexible and being formed with the irregular edge of the straw braid directed outwardly from the tip, the lower portion of the crown and the inner portion of the brim being relatively soft and flexible and formed with the smooth edge of the straw braid directed outwardly away from the tip.

25 12. In straw hat construction, a stiffened straw hat comprising overlapping rows of straw braid having an irregular edge and a smooth edge, the brim being made of the same straw braid throughout and the inner portion of the brim of said hat being relatively soft and the smooth edge of the straw braid overlapping the irregular edge at said portion.

30 13. In straw hat construction, a straw hat comprising overlapping rows of straw braid having an irregular edge and a smooth edge, the outer portion of the brim being relatively stiff and the inner portion of the brim being relatively soft, the irregular edge of the straw braid overlapping the smooth edge at said outer portion and the smooth edge of the straw braid overlapping the irregular edge at said inner portion.

35 14. In straw hat construction, a straw hat having a brim which comprises overlapping rows of straw braid sewed together, said braid having an irregular edge and a smooth edge, the outer portion of the brim being relatively stiff and the inner portion of the brim being relatively flexible, the straw braid at said outer portion being positioned with the irregular edge overlapping the smooth edge and being sewed with a concealed stitch, the straw braid at said inner portion being positioned with the smooth edge overlapping the irregular edge and being sewed with a stitch different from and more firm than said concealed stitch.

40 15. The herein described art of making straw hats, which consists in sewing a strip of straw braid having an irregular edge and a smooth edge in a spiral with the irregular edge thereof directed away from the tip of the hat and overlapping the smooth edge from the tip to a point adjacent the band, reversing the strip and sewing from said point with the smooth edge directed away from the tip and overlapping the irregular edge.

45 16. The herein described art of making straw hats, which consists in sewing a strip of straw braid having an irregular edge and a smooth edge in a spiral with the irregular edge thereof directed away from the tip of the hat and overlapping the smooth edge from the tip to a point adjacent the band, reversing said strip and sewing from said point to a point on the brim with the smooth edge of the strip directed away from the tip and overlapping the irregular edge, again reversing the strip and sewing from said second point to the edge of the brim with the irregular edge of the strip directed away from the tip and overlapping the smooth edge.

50 17. The herein described art of making straw hats, which consists in sewing a strip of straw braid having an irregular edge and a smooth edge in a spiral with the smooth edge thereof directed outwardly away from the tip of the hat and overlapping the irregular edge from the band portion of the hat to a point on the brim, reversing the strip and sewing from said point to the edge of the brim with the irregular edge of the strip directed outwardly from the tip and overlapping the smooth edge.

55 18. The herein described art of making straw hats, which consists in sewing with a concealed stitch a strip of straw braid having an irregular edge and a smooth edge in a spiral with the irregular edge thereof directed away from the tip of the hat and overlapping the smooth edge from the tip to a point adjacent the band, reversing the

strip and sewing from said point with a through and through stitch and with the smooth edge directed away from the tip and overlapping the irregular edge.

5 19. The herein described art of making straw hats, which consists in sewing, in a spiral and with a suitable stitch, a strip of straw braid having an irregular edge and a smooth edge, with the irregular edge over-
10 lapping the smooth edge, to a point adjacent

the band, reversing the strip so that the smooth edge overlaps the irregular edge, and continuing the sewing of the spiral from said point on but with a stitch different from and more firm than said first-mentioned 15

stitch.

In testimony whereof, I have signed my name to this specification this 4th day of September, 1924.

GEORGE H. CROFUT.
